UNITED STATES PATENT OFFICE.

JOHN S. HANSEN, OF BROCKTON, MASSACHUSETTS, ASSIGNOR TO O. A. MILLER TREING MACHINE COMPANY, OF PORTLAND, MAINE, A CORPORATION OF MAINE.

ELECTRICALLY-HEATED TOOL.

1,136,127.

Specification of Letters Patent.

Patented Apr. 20, 1915.

Application filed August 24, 1912. Serial No. 716,843.

To all whom it may concern:

Be it known that I, JOHN S. HANSEN, a citizen of the United States, residing at Brockton, in the county of Plymouth and Commonwealth of Massachusetts, have invented certain Improvements in Electrically-Heated Tools, of which the following description, in connection with the accompanying drawings, is a specification, like reference characters on the drawings indicating like parts in the several figures.

This invention relates to electrically heated tools and is herein disclosed as embodied in a treeing iron of the type commonly used in shoe factories to smooth out the uppers of boots and shoes.

The invention aims particularly to devise an electrically heated tool which shall afford ready access to the heating resistance, which shall have provision for protecting the supply conductors for the resistance and which can be cheaply manufactured.

The invention will be readily understood from the following description when read in connection with the accompanying drawings, in which,—

Figure 1 is a view in side elevation of a treeing iron embodying this invention; Fig. 2 is a central longitudinal sectional view of the iron shown in Fig. 1; Fig. 3 is a sectional view on the line 3—3, Fig. 2; and Fig. 4 is a sectional view on the line 4—4, Fig. 2.

Referring to the drawings, 2 indicates the body of the tool which is of a common shape, and is drilled from one end nearly through to the other to form a chamber for a heating resistance unit 4. This resistance unit has a substantially cylindrical body and an oblong projection 6 at one end that supports two binding posts 7 and fits snugly in a slot 9, see Fig. 4, formed in one end of the body. The opposite end of the body is provided with a cover plate 8 shaped to close the chamber, this cover being held in position by two screws 10. A rod 12 is fixed in the cover 8 and carries a handle 14 which is secured thereon by a nut threaded on the end of the rod and operating to clamp the handle against a shoulder formed on the rod.

Two rods 16 are threaded into the end of the body 2 opposite the cover 8 and extend through a handle 18 which is clamped rigidly thereon by means of coöperating collars 20 and nuts 22. Formed through this

handle is an axial bore 24 for the reception of a pair of conductors 26 that are connected to the binding posts 7 of the resistance unit 4, and serve to conduct current thereto. A sleeve 28 of insulating material fits snugly over the binding posts and the adjacent portions of the conductors which otherwise would be exposed and in danger of becoming short circuited or of being touched by the workman. Since the forces tending to pull the conductors out of the handle when the tool is in use, might disturb the connection between the conductors and the resistance, the conductors are both fastened to the tool at a point back of their connection with the binding posts by means of a split clamp 30 having portions that embrace one of the rods 16 and other portions embracing the conductors. A screw 32 binds the parts of the clamp securely on the rod and conductors. A closely wound spiral spring 34, through which the conductors 26 extend, is fitted snugly into the outer end of the bore 24 and prevents the kinking or too abrupt bending of the conductors.

Assuming the parts to be assembled in the condition shown, the resistance may be removed by taking off the cover plate 8, loosening the clamp 30 and pushing the conductors 26 through the handle until the resistance unit 4 has been moved out of the body of the iron far enough to enable the workman to get hold of it. It may then be pulled entirely out of the iron and disconnected from the conductors. To replace it, it is merely necessary to reverse these operations.

Having thus described my invention, what I claim as new and desire to secure by Letters Patent of the United States is:—

1. A treeing iron comprising a body having a chamber for the reception of a heating resistance, a pair of opposite handles for said body, a plurality of rods rigidly supported by said body and extending into and supporting one of said handles, an electrical conductor for said resistance extending through said handle, and a cover for said chamber supported by one of said handles and removable from said body independently of the other handle.

2. A treeing iron comprising a body having a chamber for the reception of a heating resistance, a handle having a bore formed therethrough, two rods supported rigidly in

said body, and extending through said handle at opposite sides of said bore, coöperating collars and nuts on said rods for clamping the handle thereon, supply conductors for said resistance extending through said bore, and means for clamping said conductors to a part of the iron at a point behind their connection with the resistance.

3. A treeing iron comprising a body having a chamber formed longitudinally therethrough, a heating resistance positioned in said chamber, a removable cover for one end of said chamber, a handle supported by said cover, two rods supported rigidly in the end 10 of said body opposite said cover, a handle supported on said rods, said handle having 15

an axial bore formed therethrough, supply conductors extending through said bore and connected to said resistance, a clamp embracing said conductors and one of said rods, and an insulating sleeve positioned between said rods and inclosing the connection between said conductors and said resistance.

In testimony whereof I have signed my name to this specification in the presence of two subscribing witnesses.

JOHN S. HANSEN.
